UNITED STATES PATENT OFFICE.

JULIUS B. WANTZ, OF CHICAGO, ILLINOIS, ASSIGNOR TO VICTOR ELECTRIC COMPANY, A CORPORATION OF ILLINOIS.

EAR-PUMP.

SPECIFICATION forming part of Letters Patent No. 728,526, dated May 19, 1903.

Application filed February 11, 1903. Serial No. 142,976. (No model.)

To all whom it may concern:

Be it known that I, JULIUS B. WANTZ, a citizen of the United States, residing at Chicago, in the county of Cook and State of Illinois, have invented a new and useful Improvement in Ear-Pumps, of which the following is a specification.

My object is to provide a particularly simple and desirable pneumatic pump of improved construction and capable of ready adjustment to effect suction alone or suction with release or vibrations brought about by alternate suction and compression or compression alone.

15 The pump is more especially adapted for use with any suitable tip for insertion into the ear of a patient, when the device may be employed for exercising or massaging pneumatically the tympanum in the treatment of certain diseases of the ear.

In carrying out my invention I provide a small piston-pump fitted at its base with a rotary slide-valve, which may be turned to and held in any one of four positions to bring about the results above stated. In use the valve is connected to a hose (not shown) carrying a tip, earpiece, or cup for any massaging purpose.

Referring to the drawings, Figure 1 is a 30 view of my improved pump, partly in side elevation and partly in section, showing the valve portion turned to the position wherein it produces compression alone; Fig. 2, a broken section taken on line 2 in Fig. 1 and showing the means for adjusting the stroke of the pump-piston; Fig. 3, an enlarged broken section of the pump, showing the valve turned to the suction position; Figs. 4, 5, and 6, broken sections taken on lines 4, 5, and 6 in 35 Figs. 11, 7, 8, and 10, respectively; Figs. 7 and 8, plan views of the meeting faces of the valve and valve-seat, the views being taken on dotted lines 7 and 8 in Fig. 3 and viewed as indicated by the arrows; Fig. 9, a broken 40 plan section taken on line 9 in Fig. 3, the valve being in the compression position; Figs. 10, 11, and 12, plan sectional views on line 9 in Fig. 3, but showing, respectively, the valve turned to vibration, suction and 45 release, and suction positions; and Fig. 13, a perspective view of one of several similar 50

screw-plugs in the valve-seat portion of the pump which confine and limit the movement of the ball-valves in the air-passages.

A is a pump-stand provided toward its upper end with a shaft-bearing opening *a* and toward its lower end with a rock-shaft-bearing opening *b*. In the bearing *a* is a drive-shaft *B*, carrying at its rear end a drive-pulley *c* and at its forward end a head or disk *C*. 55

D is a pump-cylinder mounted near its base on a horizontal rock-shaft *d*, extending into the bearing-opening *b*. In the shaft *d* is an annular groove *d'*, into which extends a screw *d''*, passing through the stand and confining the rock-shaft against longitudinal play. The rear end of the opening *b* is closed in the present construction by an ornamental plug *e*. Working in the cylinder *D* is a piston *E* on the lower end of a stem *E'*. 60

Extending through the disk or head *C* at right angles to the shaft *B* is an opening *f*, from which, at one side of its axis of rotation, extends a slot *f'* of less width than the opening *f*. The head of the piston-stem forms a bearing-ring *E''*. 65 A thumb-screw *g*, having a cylindrical shank *g'* and a threaded shank extension *g''*, passes at the shank *g'* through and forms a bearing for the ring portion *E''*. Between the ring and the face of the face of the disk *C* is 70 a washer *g''*. The threaded part *g''* of the shank passes through the slot *f'* and carries a nut *g''* in the opening *f*. By loosening the thumb-screw *g* it and the parts carried thereby may be slid toward and away 75 from the center of rotation of the disk *C* to diminish or increase the throw of the pump-piston and tighten it in the adjusted position.

The lower end or head *D'* of the cylinder presents a flat valve-seat or meeting face *h* 80 for the meeting or seating face *i* of a rotary slide-valve *F*. The valve *F* is upon a bolt *G*, having a plain shank portion *k*, head *k'*, and threaded end *k''*. The bolt passes at its shank *k* through a central opening in the valve, and the part *k''* is screwed into a threaded socket in the head *D'*. Surrounding the shank *k* and confined between the head *k'* and the under side of the valve *F* is a spring *G'*, which operates to press the valve yieldingly to its seat without interfering with its rotation. 85

Extending through the valve in the posi-

tion shown is a port or passage *l*, and diametrically opposite thereto is a port or passage *m*, extending from the face of the valve out through one side thereof and terminating in a hollow handle or projection *m'*, adapted to fit into the end of a rubber hose. (Not shown.) Extending from the face *h* through the cylinder-head to the interior of the cylinder are passages *n*, *p*, *r*, *s*, and *t*. In the passage *n* is a chamber *n'*, containing a ball-valve *n*², seating downward. In the upper end of the said passage is a hollow screw-plug *w*, which limits the rise of the ball-valve, but contains slots *w'* to prevent closing of the passage when the ball is raised against its lower end. In the passage *p* is a chamber *p'*, containing a ball-valve *p*², which seats upward, its movement away from the seat being limited by a screw-plug *w*, like the one described. In the passage *r* is a chamber *r'*, containing an upwardly-seating ball-valve *r*², the distance of movement of said valve from its seat being limited by a screw-plug *w*, similar to the one described. The passages *s* *t* contain no chambers or valves.

The valve *F* may be turned upon the pin or bolt *G* a half-revolution, this movement being limited by stops *y*, fastened to the head *D'* and extending downward into the path of the projection or handle *m'*. When turned to one stop, as shown in Fig. 3, the ports *l* *p* are brought into register and also the ports *m* *n*. This is what is termed the "suction position." Rise of the piston *E* sucks air through the port *m* and discharges it through the port *l*. Thus in operation when, for example, the earpiece is inserted into the ear of the patient it tends toward producing a vacuum at the outer side of the ear-drum.

When the valve is turned to the reverse position, whereby the port *m* registers with the port *p* and the port *l* registers with the port *n*, the piston draws air through the port *l* and forces it through the port *m* to exert compression against the ear-drum. When the valve is turned to the position shown in Figs. 10 and 6, the port *l* is blanked and the port *m* registers with the port *t*. In this position the piston in its downstroke forces air against the ear-drum and its upstroke withdraws the air therefrom, producing alternate compression and suction or "vibrations," as it is termed.

When the valve is turned to the position shown in Figs. 11 and 4, the port *l* registers with the port *r* and the port *m* registers with the port *s*. When in this position the rise of the plunger sucks air through the port *m* and in its descent may force the air simultaneously through the ports *m* *l*. This has the effect of producing alternate suction and release upon the tympanum.

In the head *D'* is the spring plunger-pin *x*, and in the face of the valve are shallow sockets *z* *z'*. The plunger-pin is in the path of the said sockets and operates to engage one or the other when moved into register there-

with. The engagement, though gentle, is sufficient to indicate to the operator the position of the valve, but does not interfere materially with the movement of the valve from one position to another.

The rocking of the cylinder upon its bearing at *d* maintains it always in line with the piston-stem. The construction shown and described renders it very easy to turn the valve to any position desired quickly and accurately. The spring *G'* operates to hold the rotary slide-valve yieldingly against its seat, whereby under too great pressure through the passage *m* it will open, and thus prevent undue compression. The tension of the spring may be varied, if desired, by turning the screw *G*.

While I prefer to construct my improvements throughout as shown and described, they may be variously modified in the matter of details of construction without departing from the spirit of my invention as defined by the claims.

What I claim as new, and desire to secure by Letters Patent, is—

1. In a pump of the character described, a cylinder having a valve-seat provided with valved ports and open ports extending to the interior of the cylinder, and a main movable valve on said seat provided with passages adapted to register successively in the movement of the main valve with different said valve-seat ports, and operate under the action of the pump according to the relative positions of the main valve to effect compression, suction, suction and release, or vibration, substantially as described.

2. In a pump of the character described, a cylinder having a valve-seat provided with valved ports and open ports extending to the interior of the cylinder, and a rotary slide-valve on said seat provided with passages adapted to register successively in the movement of the slide-valve with different said valve-seat ports, and operate under the action of the pump according to the relative positions of the slide-valve to effect compression, suction, suction and release, or vibration, substantially as described.

3. In a pump of the character described, a cylinder-head having a valve-seat provided with individually-valved ports *n* *p* *r* and open ports *s* *t*, all communicating with the interior of the cylinder, and a rotary slide-valve on said seat having the passages *l* *m* adapted to register in the movement of the slide-valve with said ports, substantially as and for the purpose set forth.

4. In a pump of the character described, a cylinder-head having a valve-seat provided with valved ports and open ports communicating with the interior of the cylinder, and a yielding, spring-pressed, rotary slide-valve on said seat having passages adapted to register in the movement of the slide-valve with said ports, substantially as and for the purpose set forth.

5. In a pump of the character described, a cylinder-head having a valve-seat provided with individually-valved ports $n\ p\ r$ and open ports $s\ t$, all communicating with the interior of the cylinder, and a yielding, spring-pressed, rotary slide-valve on said seat having the passages $l\ m$ adapted to register in the movement of the slide-valve with said ports, and a hol- low tubular extension m' on the slide-valve registering with the passage m , all constructed and arranged to operate substantially as and for the purpose set forth.

JULIUS B. WANTZ.

In presence of—

WALTER WINBERG,
Wm. B. DAVIES.
